UNITED STATES PATENT OFFICE.

GUSTAV EDMUND REINHARDT, OF LEIPSIC, GERMANY.

TOOL-HOLDER-OSCILLATING DEVICE FOR PLANING-MACHINES.

SPECIFICATION forming part of Letters Patent No. 339,212, dated April 6, 1886.

Application filed July 22, 1885. Serial No. 172,264. (No model.)

To all whom it may concern:

Be it known that I, GUSTAV EDMUND REINHARDT, a citizen of Germany, residing at Leipsic, in the Empire of Germany, have invented a new and useful Improvement in Tool-Holder-Oscillating Devices for Planing-Machines, of which the following is a full and exact specification.

This invention relates to improvements on planing-machines; and it consists in novel mechanism whereby a swinging motion is communicated to the tool-holder. This will enable a double-edged cutter to cut or plane during the forward as well as during the backward motion of the machine.

In the accompanying drawings, Figure 1 is a front view of a support of a planing-machine. Fig. 2 is a cross-section of the same. Fig. 3 is a back view of the carriage, partly in section; 20 and Figs. 4, 5, and 6 are details referred to in the following specification.

The cross-slide A is fitted upon the vertical slide B, attached to the upright frame of the machine (not shown in the drawings.) This cross-slide A receives sidewise motion by means of the screw C, operated by the pawls b' b'', arranged on the levers c' c''. These levers are connected to the rod a, which receives motion in the usual manner. The arm c'' is 25 elongated and connected by rod d with a lever, e, placed upon a shaft, f, so as to be capable of turning freely upon the same. This shaft f is supported parallel to the feed-screw c, by brackets f' f'', attached to the vertical slide B. 30 Close to the lever e there is firmly attached to the shaft f a disk, g. This disk g is provided with studs h' h'', capable of being regulated and against which the lever e is made to strike, and to thus communicate the desired motion to the shaft f. Upon the shaft f the bevel-gear i'' is arranged, capable of sliding in a groove on said shaft and meshing into a corresponding bevel-gear, i', connected to a wheel, k'. (See Figs. 4 and 5.) One end 35 of this bevel-gear i' is supported in a frame f'', that slides on the shaft f and straddles the bevel-gear i''. The other ends or hubs of the wheels i' and k' are supported in a lever, v, turning on a bolt, v', attached to the carriage D. This bolt v' supports a wheel, k'', that 40 meshes into the wheel k'. The wheel k'' is fastened upon the bolt v' by means of the set-

screw w, Fig. 3, to regulate its exact position. The carriage D is provided with a spindle, o'', having a fixed collar or hub, m, and a second collar, n, working on the threaded part of said spindle o''. The fixed collar or hub m is connected with the gear-wheel k'' by a rod, l, and the hub or collar n is provided with a convex projection, n', engaging a corresponding socket, p', at the back of the tool-holder p. This rod l forms the connecting-rod between the wheel k'' and the hub m, which is firmly attached to the spindle o'', as above described, and converts the rotary motion of the wheel k'' into a reciprocating motion of the hub m or spindle o''. The hub n is held fast on the threaded part of the spindle o'', and thus receives the reciprocating motion from its spindle o''. By means of the threaded part of the spindle o'', the hub n can be raised or lowered to correspond with the position of the tool-holder p. The tool-holder p turns in side bearings, r' r'', on the carriage t.

The operation of the above described mechanism is as follows: The cross-slide A, with carriages D t, and tool-holder p, receives sidewise motion on the vertical slide B by the screw C, operated by rod a in the usual manner. The motion of this rod a is communicated by arm c'' and rod d to lever e, which latter (by coming in contact with one or the other of the studs h' h'') gives an oscillating motion to the shaft f. This motion given to the shaft f is communicated by bevel-gear i'' i' and wheel k', to the wheel k'', and from the latter by the connecting-rod l to the spindle o'', thus producing a reciprocating motion of the spindle. This motion is again communicated by projection n' to the tool-holder p, turning on the bearings r' r'', thus producing an oscillating motion of said tool-holder. In this way either the one or the other side or cutting-edge of the tool q is brought into action, according to the direction of the motion of the planing-table.

In the carriage D there is placed a second screw-spindle, o', on the side of the spindle o'', and connected with the same by gearing u' u''. These gear-wheels u' u'' turn in the upper part 100 of the carriage D, and the spindles o' o'' pass through the same and are connected thereto by suitable feathers.

The spindle o' has for its object to regulate

the position of the carriage t , by passing through a boss, o^3 , attached to the carriage t , while the spindle o^2 produces the oscillation of the tool-holder p , in the manner above described.

Instead of a double-edged cutter q , two regular cutters placed side by side, with their cutting-edges in opposite directions, at about one hundred and eighty degrees to each other, may be employed for the purpose.

What I claim as my invention, and desire to secure by Letters Patent, is—

1. In a planing-machine, the combination of reciprocating spindle o^2 with hub n , having projection n' , and with tool-holder p , having socket p' , and with rod l and collar m , substantially as and for the purpose described.

2. The combination of cross-slide A, oper-

ated by feed-screw C, with the spindle o^2 , bevel-gear i^2 , wheels $k' k^2$, rod l , and shaft f , the shaft f and screw C receiving motion from rod a by means of intermediate gearing, substantially as specified.

3. The combination of tool-holder p , oscillating on centers $r' r^2$, with reciprocating spindle o^2 , rod l , collars $m n$, and with screw o' and wheels $u' u^2$, as and for the purpose set forth.

In testimony whereof I have signed my name to this specification in the presence of two subscribing witnesses.

GUSTAV EDMUND REINHARDT.
